UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

LATCH CONSTRUCTION.

Application filed November 2, 1926. Serial No. 145,733.

This invention relates to a latch mechanism. More particularly it relates to a latch mechanism especially adapted for use upon the doors of closed automobile bodies, although, of course, it could also be used upon any other form of door.

It is well known that the aim of automobile body builders in constructing closed bodies is to reduce as much as possible the size of the corner and door posts and to increase the width of the windows in order to procure a maximum freedom of vision from within the body. Necessarily the latch mechanism for the doors is a controlling factor in so far as the door windows are concerned, since the position of the spindle connecting the outer operating handle with the latch bolt ordinarily limits the width of such windows.

In order to overcome this difficulty it has been proposed to have these spindles circumvent the edges of the path of movement of the window pane. Several methods of accomplishing this circumvention have been described in a number of my co-pending applications.

The principal object of this invention is to provide an efficient, practical and economical arrangement for effecting a circumvention of the edge of the window pane by the means connecting the outside operating device with the latch bolt.

Additional objects and advantages will become apparent from time to time as the description proceeds.

In order to allow a window pane of substantially the full width of the door to be used, the invention contemplates having the means connecting the outside operator with the latch bolt pass transversely of the door in substantially the same vertical plane as the face of the latch casing adjacent the jamb edge of the door.

This arrangement is conveniently brought about by offsetting outwardly the bight of the latch casing so as to form a transversely extending semi-circular portion therein, and securing in cooperative relationship thereto a separate cap member, having an offset corresponding thereto but extending in the opposite direction whereby a substantially circular bearing is formed in which the inter-

connecting or interlocking member may oscillate.

The interior of the door is provided, for purposes of convenience, with a remote inside latch operating means.

The preferred embodiment of the invention is illustrated in the accompanying drawings, wherein

Fig. 1 shows in top plan view the latch mechanism and inside and outside operators therefor, the door being indicated in dotted lines.

Fig. 2 shows the latch mechanism in side elevation, looking toward the outside operator, the mechanism being removed from the door and the link connecting the inner operators being shown as broken away.

Fig. 3 shows in side elevation the remote inner operator, looking from line 3-3 of Fig. 1, in the direction of the arrows.

Fig. 4 shows in side elevation the latch mechanism and adjacent inner operator, looking from line 4-4 of Fig. 1, in the direction of the arrows.

Fig. 5 shows the latch mechanism and casing in side elevation, and

Fig. 6 shows the outside operator looking from line 6-6 of Fig. 1, in the direction of the arrows.

The latch mechanism is adapted to be arranged within the pocket or well of an automobile door 1, indicated in Fig. 1 in dotted lines. It comprises an outside operator 2, a latch mechanism proper 3, and a remote inner operator 4.

A substantially U-shaped casing having one arm 6 secured to the inside of the inner door panels, another arm 7 secured to the outer door panel and a bight portion 8 arranged substantially adjacent to the jamb face of the door is adapted to support the latch mechanism. The bight portion 8 is provided with an offset 9, semicircular in cross section, which extends transversely thereof. The purpose of this offset portion will become apparent as the description proceeds.

The latch mechanism proper is carried by the arm 6 of the latch casing. This mechanism comprises a bolt head 10 and follower plate 11 connected thereto. This plate is offset outwardly at 12 toward the latch cas-

ing, thus affording a clearance to accommodate certain elements of the mechanism to be mentioned later. The lower side of the plate is provided with a downwardly and forwardly projecting portion 13 having an inclined lateral flange 14 at its end. This projection is adjacent the forward end of the plate, while in the lower edge near the rear end a notch 15 is provided. One end 5 of the main latch spring 16 enters this notch and engages the plate to force the same forwardly to projected position. The outer end of the spring is anchored between tabs 17 and 18 struck up from the latch casing. 10 A second plate 19, offset at 20 in a manner similar to the follower plate, is adapted to be superimposed upon said follower so as to have a lost motion connection therewith. This is accomplished by providing the plate 15 with elongated slots 21 and 22 near opposite ends thereof through which project pins carried by the follower plate and having enlarged heads 23. It will thus be seen that the bolt head and follower plate may 20 be moved inwardly a distance equal to the length of the slots before such movement is transmitted to the plate 19, while on the other hand a rearward movement of the plate is transmitted to the follower plate and bolt 25 head immediately. The plate 19 extends rearwardly from the slot 21 a short distance where the end thereof is connected with a link 24, the purpose of which will be further explained. This connection likewise 30 constitutes a lost motion connection, since a pin 25 carried by the plate has a sliding engagement within a slot 26 formed in the end of the link.

The follower plate is adapted to have 35 sliding movement on the latch casing, being guided therein by the opening in the bight 8 through which the bolt head passes and by guide members 27 and 28 formed on the casing.

The inside operator 4 is carried by a plate 29 secured to the inner door panel at a point remote from the latch mechanism. A cover plate 30 is secured to the plate 29 but is spaced therefrom. A spindle 31, adapted 40 to have an operating handle (not shown) on its inner end, is rotatably carried in an opening formed in the inner door panel and the plate 29. The end of this spindle within the pocket or well of the door is squared to receive a connecting follower member 32. This end projects through the cover plate and has a nut or other fastening member arranged thereon. The lower end of the connecting member has a pin 33 extending 45 through a slot 34 in the end of the link 24, opposite to the slot 26. A nut 35 is secured on the end of this pin. The description and drawings clearly disclose the construction, showing that the link 24 is connected at its 50 opposite ends with lost motion connections.

A spring 36, having one end secured to the cover plate 30 and the other end bearing against the follower member 32 tends to maintain the parts in their normal relation.

It is thus apparent that rotation of the spindle 31, so as to cause the member 32 and link 24 to move toward the hinged edge of the door, will correspondingly move the plate 19, follower plate 11 and bolt head 10, thus retracting the latch bolt. Also, it is clear that upon the inner operating handle being released, the springs 16 and 36 will return the parts to their normal position. Further, it will also be readily understood that closing movement of the door will 70 cam the bolt head inwardly, because of its beveled nose, and that this movement will be independent of the plate 19, link 24 and member 32, due to the lost motion connections therewith.

It has been previously brought out that the bight portion 8 of the latch casing is provided with a transverse outwardly offset part 9, substantially semi-circular in cross-section. This offset part is adapted to receive a yoke member 37, indicated generally in Fig. 5. After the yoke member has been arranged within the offset part a cap member 38 is secured to the bight portion in complementary relationship with the offset 9. 90 This member has attaching flanges 39 and 40, which may be secured to the latch casing by means of rivets, screws, or other suitable securing members. It will be readily seen that the parts 9 and 38 form a substantially cylindrical bearing for the yoke 37, the part of which passes therethrough lying approximately within the plane of the bight portion of the latch casing.

The yoke 37 comprises a central part 41, adapted to be received within the bearing above described, and arms 42 and 43 extending inwardly from opposite ends of the part 41. These arms pass inwardly into the latch casing through openings provided in the face of the bight portion. The arm 42 is arranged adjacent the outside of the door and is adapted to be connected with the outside operating means.

The outside operator 2 comprises a spindle 115 rotatably mounted in bearings formed by openings in the outside door panel, plate 7 of the latch casing, and in a cover plate 45 secured upon the plate 7. The outer end of the spindle is provided with an operating handle (not shown). Mounted upon this spindle for rotation therewith is an arm 46. This arm is connected to a link member 47, which in turn is connected to the arm 42 of the yoke. A spring 48, having one end bearing against the rear edge of the arm 46 and the other end anchored between lugs 49 and 50 struck up from plate 7, maintains the parts of the outside operator in their 120 normal position.

The inner arm 43 of the yoke is provided with a laterally offset part having a head portion 51. The edge 52 of this portion adjacent to the lateral flange 14 of follower plate 11 is inclined in a manner corresponding to the incline on the edge of the said flange.

Rotative movement of the spindle 44 will be transmitted through members 46 and 47

- 10 to the arm 42 of the yoke. The yoke, being a single or integral member, will thus be rotated in its bearings, whereupon arm 43 will swing downwardly so that the inclined edge 52 of the head portion 51 thereof will 75 exert a wiping or camming action upon the flange 14 thus effecting retraction of the bolt. The spring 48 should be of such tension that it will, of itself, return the parts to normal position upon release of the outside operating handle.

In order that the latch bolt may be secured from the inside against operation from the outside, the following mechanism is used.

25 A locking or dogging lever indicated generally as 53 is slidably mounted on the arm 6 of the latch casing beneath the offset 12 of the follower plate 11. This lever is guided in its vertical sliding movement by a pin

30 54 and slot 55. The slot may be located in the lever or in the arm 6, as desired, and, of course, the pin would be inversely located. A bowed spring 56 is also mounted on the pin and engages the under side of a latch

35 casing cover plate to hold the lever against rattling. An outwardly extending portion 57 is provided on the lever approximately in line with the pin, and this portion has a lateral flange 58 which is also adapted to

40 bear against the latch casing cover plate. The lever extends downwardly beneath the offset portion of the follower plate being gradually inclined forwardly until near the end thereof where it is provided with a portion

45 59 lying at approximately a right angle to the vertical portion. The end of this portion is slightly offset inwardly as indicated at 60. The lever in its vertical extent has, near the lower end thereof, a punched out

50 protuberance 61, while the plate 6 is provided with a pair of spaced recesses 62 cooperating with said protuberance. The upper end of the lever is provided with a laterally bent portion 63, which is tapped or otherwise arranged to receive an operating stem which projects above the well or window pocket. When it is desired to dog the bolt against operation from the outside the lever is pushed downwardly the limit of the

55 slot 55, when the protuberance 61 will be snapped by the action of the spring 56 into the lower of the recesses 62. The inwardly offset part 60 of the lower portion of the lever will then be behind a part of the head 51 of the arm 43, and movement of said arm and

consequently the outside operator will be prevented. In order to release the dogging means the lever is pulled upwardly the extent of the slot until the protuberance engages the upper of the recesses, at which time the part 60 will lie behind the follower plate in the offset portion, thus giving freedom of movement to the outside operating means.

The foregoing description has set forth 75 a latch mechanism construction particularly adapted to be used on that type of automobile door having a sliding window of substantially the full width of the door. The interlocking or interconnecting means passing transversely of the door in substantially the same plane as the bight portion of the latch casing, which is adjacent to the jamb face of the door, gives ample space in which to mount a window substantially of the full 85 width of the door. The bearing for the interlocking means is readily formed by stamping operations and is capable of quick and accurate assembly. The other details of the construction present certain refinements 90 of latch mechanisms with which it is necessary at the present time to equip automobile bodies.

The invention, although illustrated by a single embodiment, is capable of other embodiments and is only limited by the scope of the appended claims.

Claims:

1. A latch mechanism for an automobile door adapted to have a window of substantially the full width of the door slidably arranged therein, comprising inside and outside latch operating devices carried upon opposite sides of the door, and an interlocking member between said devices extending 100 transversely of the door in a two part bearing member and lying substantially in the plane of the bight portion of the latch casing.

2. A latch mechanism for an automobile 110 door adapted to have a window of substantially the full width of the door slidably arranged therein comprising a latch casing, inside and outside latch operating devices carried upon opposite sides of the door, and an 115 interlocking member between said devices, said latch casing being offset outwardly to form with a cap member a transversely extending bearing for the interlocking member lying substantially in the plane of the bight 120 portion.

3. A latch mechanism for an automobile door adapted to have a window of substantially the full width of the door slidably arranged therein comprising a latch casing 125 having a bight portion adapted to be arranged adjacent the jamb edge of the door, said bight portion being provided with a transversely extending outward offset, a cap member correspondingly offset in the oppo- 130

site direction secured to said bight portion in cooperative relation with said outward offset, whereby a bearing is formed to accommodate an interlocking member between outside and inside latch operating devices.

4. A latch mechanism for an automobile door adapted to have a window of substantially the full width of the door slidably arranged therein comprising inside and outside latch operating devices carried upon opposite sides of the door, a latch casing having a bearing extending transversely of the door formed partly by an offset portion of the casing and partly by a separable member, and a yoke member, the central part of which is carried by said bearing while the arms extend into the casing upon opposite sides of the window for operatively connect-

ing the outside operator with the latch bolt.

5. A latch mechanism for an automobile door adapted to have a window of substantially the full width of the door slidably arranged therein comprising a latch casing having a portion thereof adapted to be adjacent the jamb face of the door, said portion being offset outwardly transversely of the door, a cap member secured to said casing at the offset to form a bearing, inside and outside latch operating devices carried upon opposite sides of the door, and an interlocking member between said devices carried by said bearing, whereby the same will lie substantially in the plane of the latch casing.

In testimony whereof he hereunto affixes his signature.

JOSEPH LEDWINKA.
